UNITED STATES PATENT OFFICE

CHARLES C. SPREEN, OF DETROIT, MICHIGAN, ASSIGNOR TO KELVINATOR CORPORATION, OF DETROIT, MICHIGAN, A CORPORATION OF MICHIGAN

MECHANICAL REFRIGERATION

Application filed February 21, 1937. Serial No. 169,764.

My invention relates to mechanical refrigeration, and particularly to means for increasing the heat absorbing power of a refrigeration expansion unit, and the principal object of my invention is to provide new and improved means of this type. In the drawings accompanying this specification and forming a part of this application I have shown, for purposes of illustration, two forms which my invention may assume, and in these drawings:

Figure 1 is a front elevation of one embodiment of my invention,

Figure 2 is a side elevation thereof, while Figure 3 is a front elevation of another embodiment of my invention.

The embodiment of my invention shown in Figures 1 and 2 comprises a refrigerant expansion drum 11, of the usual float valve type, and refrigerant tubes 12 attached at spaced intervals throughout the length of the drum 11 at substantially diametrically opposed points and depending below the drum 11 in the form of loops 13.

In order to increase the heat absorbing power of the expansion unit the loops 13 are encased in twin sets of receptacles 14 adapted to contain brine or similar heat conducting material thereby increasing the heat absorbing power of the loops 13 and through them of the expansion drum 11.

In the embodiment of my invention shown in Figure 3 sleeve-like receptacles 15 are disposed in the space between the twin receptacles 14 and arranged to accommodate trays 16 for the formation of artificial ice under the action of the refrigerating unit.

From the above it will be obvious to those skilled in the art that I have provided new and improved means for increasing the heat absorbing power of a refrigerant expansion unit.

At the same time it will be obvious to those skilled in the art that the embodiment of my invention herein shown and described may be variously changed and modified without departing from the spirit of my invention or sacrificing the advantages thereof, and it therefore will be understood that

the disclosure herein is illustrative only, and that my invention is not limited thereto.

I claim:

1. In refrigerating apparatus, a refrigerant expansion unit comprising a drum, pipe loops depending from said drum and in communication therewith, said pipe loops being arranged in spaced relation, and brine containers enclosing the major portions of the depending loops on each side of said drum, said brine containers being spaced in parallel relation. 55

2. In refrigerating apparatus, a refrigerant expansion unit comprising a drum, separate depending pipe loops arranged in rows 65 on each side of said drum, said pipe loops being in open communication with said drum, and separate heat transfer means thermally associated with the loops in each of said rows. 70

3. In refrigerating apparatus, a refrigerant expansion unit comprising a drum, depending pipe loops arranged in rows on each side of said drum and in communication therewith, a heat transfer means associated 75 in thermal contact with each row of pipe loops, and tray receiving sleeves secured intermediate said heat transfer means and in thermal contact therewith.

In testimony whereof I hereunto affix my 80 signature.

CHARLES C. SPREEN.
